F. C. HARE

BROODER

Filed March 7, 1922.

UNITED STATES PATENT OFFICE.

FRANKLIN C. HARE, OF ROCKFORD, ILLINOIS.

BROODER.

Application filed March 7, 1922. Serial No. 541,788.

To all whom it may concern:

Be it known that I, FRANKLIN C. HARE, a citizen of the United States, residing at Rockford, in the county of Winnebago and 5 State of Illinois, have invented certain new and useful Improvements in Brooders, of which the following is a specification.

This invention relates to brooders for 10 hovering small chicks, and has more particular reference to the so-called "hen" brooders.

In the use of this class of brooders, it is 15 essential to the life of the chicks that the hover be properly ventilated and uniformly heated. In practice, brooders of this type are invariably heated by small liquid fuel 20 burners having wicks, and the brooders are frequently placed in the farm yard or any convenient place in the open. They are thus subject to all weather conditions. In producing brooders commercially at a low cost, considerable difficulty has been heretofore experienced in the attempt to provide one 25 which when used under the conditions mentioned will function continuously with minimum care and attention. One of the dangers is the extinguishing of the wick by wind and sudden gusts, thereby chilling the hover and 30 injuring the brood; another is lack of proper means for ventilation; and another is the lack of proper provision for inspecting 35 and regulating the height of the flame, and consequently the temperature of the hover. These conditions I have aimed to improve by the provision of a hover of simple and 40 novel construction.

Among the objects of my invention are to 45 provide a novel means for permitting quick and easy inspection of the flame without disturbing to the slightest degree the temperature of the hover; to provide an improved heater; to generally improve and simplify the construction and arrangement of the brooder casing and the heater therein; and 50 to provide a novel fence adjustably associated with the brooder casing to provide a run, the area of which may be changed at will to suit the different stages of brooding, and also to provide a closure for the hover, 55 which may be closed at any time to keep in the chicks.

Another object is to provide a brooder which may be produced and shipped economically.

Other objects and attendant advantages

will be appreciated by those skilled in the art as the invention becomes better understood by reference to the following description when considered in connection with the accompanying drawings, in which—⁶⁰

Figure 1 is a top view of a brooder embodying my invention;

Fig. 2, a vertical section taken substantially on the line 2—2 of Fig. 1;

Fig. 3, a side view looking at the right ⁶⁵ hand side of Fig. 1; and

Fig. 4, a detail section taken substantially on the line 4—4 of Fig. 2.

The brooder casing may be of any suitable or preferred construction, and in the present instance I have made it rectangular in form, comprising a quadrilateral bottom 6, upright walls 7, 8 and 9 at three sides of the bottom and a top 11 having a depending marginal flange 12 overhanging the side walls. This casing incloses the hover compartment and leaves an open side which is reinforced by upper and lower cross bars 13 and 14 respectively, and upright end bars 15. The rectangular frame 13—14—15 defines the entrance to the hover, and this entrance way or opening is normally closed by a curtain 16 suspended from the top frame bar 13. This curtain may be of any suitable material, but in practice it is preferred that it shall be of any commercial oil cloth, scalloped or slotted as shown at the bottom, to allow easy passage for the chicks and also to permit ingress of air.⁷⁰

The open side of the hover may be further closed by means of a vertical end wall 17 which is secured to side walls 18. These side walls are slidable upon the bottom 6 along the outer sides of the side walls 7 and 9, but retained against outward displacement by depending sheet metal guides 19. The fence formed by the parts 17 and 18 may thus be slid inwardly and outwardly on the brooder casing in drawer fashion to provide a fenced in area 21, commonly known as a run for the chicks. The area of this run may obviously be varied from day to day to suit the particular stage of the brood and at any time the fence frame may be pushed all the way in so that the end wall 17 entirely closes the open curtain-covered side of the hover. Holes 22 in the wall 17 admit sufficient air to the hover when the wall 17 is in closed position. These holes also serve as finger grips for opening and ⁸⁵

closing the fence frame. The advantages of having a run adjustable as to area in the manner afforded herein will be appreciated by those familiar with this art as it enables 5 the area of the run to be gradually increased with the growth of the chicks, and when desired the run may be closed entirely in a very simple manner.

The heater of novel construction, I position 10 on the floor 6 in the center of the hover. The heater structure comprises in its present embodiment a base designated generally by 23 shaped to provide a liquid fuel container and also to support the wick and other parts. The upper wall of the container is conical as shown, and has a threaded opening 15 at its apex for the reception of a wick holder 24, which carries a wick 25 adapted to be fed up and down by turning the finger piece 26. It will be observed that this finger piece is carried by a wick-adjusting shaft 27 which extends through an opening 28 in a cylindrical apron 29 which is removably supported on the container 23. An upstanding 20 annular retaining wall 31 fixed to the top of the container 23 holds the apron 29 in position and constitutes a dirt guard for preventing the admission of sand, dirt and other foreign matter in the hover from entering the burner compartment. This retaining 25 wall also provides a shield or baffle at the air inlet 28 for preventing any lateral gust or current of air from entering the burner compartment and extinguishing the flame. There is supported on the apron 29 a heater hood comprising a flat bottom disk 32 and a conical top 33, the latter of which terminates in a chimney 34 fitting loosely in an opening 35 in the top 11. There are four 30 equally spaced openings 36 through the hood bottom 32 near the apron through which openings the heated air passes upwardly into the hood. The hood compartment is divided vertically by a partition 37 which is imperforate except for four equally spaced openings 38 in its periphery. This partition 37 constitutes a baffle causing the heated air to travel outwardly from the openings 36 to the outer edge of the hood. The heated air 35 and fumes pass upwardly through the openings 38 and thence through the chimney 34 to the outer atmosphere. It will be observed that the burner compartment is closed to the admission of air except through the opening 40 28. This opening provides just sufficient air to support proper combustion of the wick. By reason of the circuitous path which the heated air is caused to travel, the heat will be retained in the hood for a sufficient period to throw off its heat properties and to enable the maintenance of a steady 45 temperature with a low flame. It will be observed that the chimney is flush with the top of the brooder casing, consequently it is not an obstruction subject to injury. This

flush top chimney construction and arrangement of the baffle plate 37 prevent extinguishing the flame by back drafts or currents which might be caused by sudden gusts of 70 wind.

My invention contemplates novel means for quickly, easily and accurately ascertaining at any time the height of the flame without disturbing any of the parts of the brooder or heater. In other words, I have 75 provided means whereby the attendant may from a standing position above the brooder, instantly determine the actual height of the flame. To this end I have provided in one side of the apron 29, an opening 39 covered by a piece of suitable transparent material, such as isinglass 41. At the outer side of the apron I have supported in radial alignment with the opening 39 and the flame of the wick, a reflector surface 42, preferably 80 in the form of a mirror. In the present instance, a suitable bracket 43 supports the mirror 42 in a position at 45 degrees with respect to the vertical so as to reflect the vision of the flame upwardly through a sight 85 passage 44 in the heater hood and through a sight opening 45 in the cover 11, which opening is closed by a piece of isinglass 46. It will thus be seen that a sight opening is provided in the top of the brooder, whereby 90 the precise condition and height of the flame may be instantly ascertained. It will be observed that the means to this end are not subjected to the flame, and consequently will not become sooted. Instead, the condition of 95 the flame is ever present in the sight opening and the attendant may very quickly and conveniently inspect any number of brooders without disturbing in any way the temperature in the hovers.

In using a brooder such as described herein, the desired temperature may be maintained in the hover with a comparatively small flame, because of the fact that the heat is retained and utilized to the best advantage. The flame is fully protected against drafts and wind, thereby promoting practicability and insuring safety to the chicks. The matter of flame inspection by actual vision of the flame image from above 105 is also highly desirable. The adjustable run enables the proper care of the chicks and promotes efficiency.

It is believed that the foregoing conveys a clear understanding of the objects prefaced above, and while I have illustrated but a single working embodiment it should be understood that considerable change might be made in the construction without departing 110 from the spirit and scope of the invention 115 as expressed in the appended claims.

I claim:

1. In a brooder, the combination of a casting providing a hover, a liquid fuel container therein, an upright annular retain- 120 125 130

ing wall on the top wall of said fuel container, an annular apron supported on said top wall spaced within said retaining wall and having an opening for the ingress of 5 air, a wick burner supported on the container within said apron, a heater hood supported on said apron and having a chimney through the top of the hover casing, said heater hood over-reaching the apron and 10 having means for causing the heated air rising from the space within the apron to travel outwardly in the hood beyond said apron before reaching the chimney.

2. A brooder of the character described, 15 comprising a hover, a chick-supporting base and a burner thereon within the hover, a vertical wall about the burner defining a heater compartment above said base, a heater hood supported on said vertical wall 20 and having a flue outlet through the top of the hover, said heater hood over-reaching the sides of said heater compartment, a reflector positioned at the outer side of said heater compartment wall for reflecting the image 25 of the burner flame upwardly, and a sight passage through the overhanging portion of the heater hood through which said image of the flame may be viewed from above the brooder.

30 3. A brooder of the character described, comprising a hover casing and a heater unit within said casing carrying means whereby the image of the burner flame may be viewed through the top of said casing, said heater 35 unit comprising a liquid fuel container, a wick-type burner supported on said container, a heater hood having a horizontally disposed heat-circulating compartment and a depending wall embracing the burner and 40 supported on said container, said wall defining a heater compartment from which the heat enters said heater hood compartment, a flue outlet from the hood compartment to the exterior of the hover casing, an 45 opening through said heater compartment wall on a level with the burner flame covered by a sheet of transparent material, means at the outer side of said wall in alignment with said opening and burner flame 50 for reflecting the image of said flame upwardly, a sight passage through the hood in vertical alignment with said reflecting means, and a sight opening in the top of the hover casing in alignment with said hood 55 passage.

4. A brooder of the character described, comprising a hover, and a heater unit within the hover comprising a chick-supporting base and a burner thereon, a warm air drum 60 around the burner, a heated hood supported on said drum and over-reaching the chick-supporting base, a reflector at the outer side of said drum supported directly thereby for reflecting the image of the burner flame upwardly, and a sight passage through the

overreaching portion of the heater hood through which said image may be viewed from above.

5. A brooder of the character described, 70 comprising a hover casing, a heater structure therein in two separable parts, one part comprising a liquid fuel container and a wick burner and the other part comprising a warm air drum adapted to rest on the container and embracing the burner, a heater 75 hood supported on top of said drum and carrying a flue outlet, a flame reflector on the outer side of and carried directly by said drum, and a sight passage through the heater hood for viewing said reflector from above.

6. In a brooder of the character described, 80 the combination of a liquid fuel container of relatively broad flat shape forming a base, a wick burner carried at a central position 85 on the container, a warm air drum supported on the container around the burner, the marginal portions of the container reaching beyond the warm air drum, a heater hood supported on said drum and overhanging said marginal portions of the container, a horizontally disposed partition in said hood dividing the same into an upper and a lower compartment, a passage connecting 90 the lower compartment and the heating 95 chamber formed by said drum, passages in the marginal portion of said partition connecting the upper and lower compartments in the hood, and a flue outlet from said upper compartment. 100

7. In a brooder of the character described, 105 the combination of a circular, comparatively flat, liquid fuel container, a burner on said container, a warm air drum of substantially less diameter than the container supported thereon surrounding the burner, a circular heater hood of substantially the same diameter as the container supported on said drum and partitioned internally to provide a circuitous air passage, whereby heated air rising from within the wall or drum will be positively caused to circulate in the portions of the hood over-reaching the drum, and a flue outlet for the hood. 110

8. In a brooder of the character described, 115 the combination of a circular liquid fuel container and a heater hood, the latter being supported on the former by a warm air drum, a burner mounted on the container within the drum, said container and heater 120 hood each being circular, relatively shallow, concentrically disposed and projecting marginally beyond the warm air drum, and means for causing warm air rising from said drum to positively pass in a circuitous path within the marginal portion of the heater hood. 125

9. In a brooder of the character described, 130 the combination of a hover casing, a liquid fuel container therein, a wick burner sup-

ported on the container, a warm air drum embracing the burner, supported upon and separable from the container and having an opening at one side reaching upwardly from its lower edge, a wick-adjusting rod connected with the burner and reaching outwardly through said opening and being operable at the exterior of the warm air drum for adjusting the wick, a deflector wall at 10 the exterior of said opening, and a heater hood supported on said drum.

10. In a brooder of the character described, the combination of a comparatively broad, circular liquid container, a wick burner at 15 a central position on said container, a warm air drum of substantially less diameter than the container supported thereon embracing the burner, and a relatively broad, circular heater hood supported on said drum with

its marginal portion overhanging the same 20 and being heated by circulation of air rising from the interior of the warm air drum.

11. In a brooder, the combination of a relatively broad and flat fuel container, a wick burner at a central position thereon, 25 an upright wall embracing the burner and providing a warm air compartment, said compartment covering only the central portion of the container and leaving the marginal portion thereof as a floor for the 30 chicks, a heater hood supported on said upright wall substantially overhanging the same and having means for causing heated air rising from said compartment to positively travel in a circuitous path in said 35 overreaching portion, and a flue outlet for the hood.

FRANKLIN C. HARE.
